UNITED STATES PATENT OFFICE

DAVID KURKCHEE, OF SCHENECTADY, NEW YORK

BED SPRING

Application filed March 31, 1932. Serial No. 602,334.

This invention relates to a bed spring which may be used with the adjustable bedstead forming the subject matter of an application filed concurrently herewith but 5 which of course, can be used with other bedsteads.

The general object of the invention is to provide means whereby the springs can be 10 adjusted as to their width so that they can be used on single or double beds or intermediate width beds.

Another object of the invention is to provide scale means whereby the springs can be 15 accurately adjusted to the desired width and to provide foldable legs for supporting the central part of the springs, particularly, when the springs are in fully open position.

A still further object of the invention is to 20 provide means whereby one side of the spring can be easily and quickly fastened to a side rail of a bed.

This invention also consists in certain 25 other features of construction and in the combination and arrangement of the several parts to be hereinafter fully described, illustrated in the accompanying drawings and specifically pointed out in the appended 30 claims.

In describing the invention in detail, reference will be had to the accompanying drawings wherein like characters denote like or 35 corresponding parts throughout the several views, and in which:—

Figure 1 is a top plan view of the improved 40 spring, this view showing the spring adjusted to a wide width in dotted lines.

Fig. 2 is a top plan view of one of the frame sections.

Fig. 3 is a similar view of the other frame 45 section.

Fig. 4 is a section on line 4—4 of Fig. 1 but with the springs adjusted to a narrow width.

Fig. 5 is a similar view but showing the 50 spring adjusted to a wide width.

Fig. 6 is a side view of the leg carrying section with the legs in folded position.

Fig. 7 is a section on line 7—7 of Fig. 2, showing how the section is connected to a side rail of a bed by the latch means.

Fig. 8 is a section on line 8—8 of Fig. 1.

Fig. 9 is a fragmentary detail view of portions of a corner of the section shown in Fig. 2, showing the brace means.

Fig. 10 is a view of one of the socket members forming part of the brace means.

Fig. 11 is a view of a brace rod.

As shown in these drawings, the spring is composed of the two frame sections A and B, each section, of course, supporting the 60 spring assembly C.

The section A is composed of the two side rails 1 and 2 and the end members 3. Each end member 3 is of channel shape in cross section with the lower flange having a vertical strip 4 connected to its outer edge and the upper edge of this strip 4 having a horizontal strip 5 connected therewith which is perforated to receive portions of the spring assembly. The side members are preferably 65 of tubular form as shown in Figs. 4 and 5 and have their ends connected to the end members by the depending brackets 6.

The side member 2, or its brackets for supporting the same, are provided with projections 7 for engaging a side member 8 of a bedstead, this member being shown in dotted lines in Figs. 4 and 5. The side member 1 has the legs 9 pivotally connected thereto as shown at 10, so that these legs can be moved 70 downwardly in vertical position to support this side of the section or can be moved upwardly when not in use as shown in Fig. 6, a pair of pivoted links 11 connecting each leg to each rail and acting as brace means for holding the legs in vertical position.

The section B is composed of but a single side member 12, preferably of tubular form and the two end members 13 to the outer ends of which the side member 12 is connected by brackets 14 which depend from the side members and are also provided with the projections 15 for engaging a side rail of a bed. The end members 13 are each of angle shape in cross section with the lower portion of the vertical member of the angle member fitting in a slidable manner in the space formed by the strip 4 and the lower part of the channel portion of an end member of section A as shown, in Fig. 8, and the end members 13 of section B are held in adjusted position in 95 100

the end members 3 of section A by the screws 14 passing through threaded holes in the reinforcing members 15 attached to the channel end members 3 with their inner ends pressing the end members 13 against the strips 4 of the end members 3.

Thus by moving the end pieces 13 of the section B in the end members 3 of the section A the width of the spring can be increased or decreased as desired, and the screws 14 act to hold the parts in adjusted position. It will of course be understood that the projections 7 on the rail 2 will engage a side rail of a bed and the projections 15 on the rail 12 of the section B will rest on the other side rail of the bed.

When the springs are adjusted to their full width or whenever desired or necessary, the legs 9 can be swung downwardly into vertical position to support the central part of the spring as shown in Fig. 5. The rail 12 of section B is slightly bowed outwardly so that it will pass under the side rail 8' of the bed, as shown in Fig. 7 and at the center, this rail 12 carries a sectional latch member 17 having one section attached to the central part of the rail 12 and its other part 17' hinged to the section 17 and of angle shape so that it can be swung over the side rail of the bed to fasten the rail 12 to the rail of the bed as shown in Fig. 7 in full lines. To release the latch means the section 17' is swung upwardly as shown in dotted lines in Fig. 7 and then the spring can be removed from the bed.

35. A brace rod 18 connects each end member 13 of the section B with the rail 12, this brace rod having its ends screw threaded to engage the internal threaded socket members 19, one of which is carried by each end member 13 and another of which is carried by the rail 12. The central part of the rod is noncircular as shown at 20 to receive a wrench or the like and it will of course be understood that the ends of the rod are provided one with left threads and the other with right threads and the sockets are correspondingly threaded. These brace means rigidly support the end members 13 from the single side rail 12 and after the end members 13 are placed in the end members 3 of the section A adjustments of the brace means are not necessary.

55. A scale strip 21 is connected to each of the end members 3 of the section A to facilitate accurate adjustment of the two sections relative to each other whereby the spring can be accurately adjusted to the desired width.

It is thought from the foregoing description that the advantages and novel features 60 of the invention will be readily apparent.

It is to be understood that changes may be made in the construction and in the combination and arrangement of the several parts provided that such changes fall within the 65 scope of the appended claim.

Having thus described my invention, what I claim as new is:—

A bed spring structure comprising a pair of sections, one section including a pair of side members and a pair of channel end members 70 having their flanges horizontally arranged and the other section including a single side member and a pair of angle end members, one limb of each angle member being horizontally arranged and its other limb depending vertically from said horizontal limb, a vertically arranged strip having its lower edge connected to the outer edge of the lower flange of each channel member, a horizontally arranged strip connected to the upper edge of 80 said vertical strip with the lower edge of the vertical limb of the end member of the second section sliding in the space which is formed by the bight of the channel member and said vertical strip, and screws carried by 85 the bight parts of the channel members for pressing the vertical limbs of the angle end members of the second section against the said vertical strips, the spring assembly of the first section being connected to the said horizontal strips and the spring assembly of the second section being connected to the horizontal limbs of the angle end members.

In testimony whereof I affix my signature.

DAVID KURKCHEE.
